UNITED STATES PATENT OFFICE.

FORREST G. PURINTON, OF WATERBURY, CONNECTICUT, ASSIGNOR TO THE PATENT
BUTTON COMPANY, OF WATERBURY, CONNECTICUT, A CORPORATION OF CON-
NECTICUT.

SEAL OR TAG FOR MEATS.

Application filed July 13, 1925. Serial No. 43,237.

To all whom it may concern:

Be it known that I, FORREST G. PURINTON, a citizen of the United States, residing at Waterbury, in the county of New Haven and State of Connecticut, have invented certain new and useful Improvements in Seals or Tags for Meats, of which the following is a specification.

My invention relates to new and useful 10 improvements in seals or tags for meat or fowl, and is especially adapted for tagging salt meat, such as hams, sides of bacon and the like.

The present application is a companion 15 one to that filed by me on May 26th, 1925, Serial Number 32,934, and to another application filed of even date herewith Serial Number 43,236.

One of the principal objects of the present invention is to provide a seal or tag, the spindle of which is formed of metal of very limited ductility, so that after the tag or seal is once applied, any tampering with the tag will cause the same to break and render 25 the tag or seal unfit for further use.

Still another object of the invention is to provide a tag or seal for meats wherein a wire or rod of aluminum of low ductility is used to form the spindle and to form an enlarged head, after which a cap is placed 30 about the head. The cap is preferably formed of aluminum of higher ductility, however, than the spindle, and is provided with a monogram, trademark, brand or other fanciful insignia.

With these and other objects in view, the invention consists in certain new and novel arrangements and combination of parts as will be hereinafter more fully described and pointed out in the claims.

Referring now to the drawings showing a preferred embodiment of my invention,

Fig. 1 is a perspective of a ham tagged or sealed with my improved seal or tag.

Fig. 2 is a fragmentary detailed section showing the manner of applying the tag or seal.

Fig. 3 is a similar fragmentary detailed section showing the tag or seal in its final position.

Fig. 4 is a fragmentary detail of a wrench, showing the curling of the end of the seal.

Fig. 4^a shows the completed curl, and the spindle slightly modified in that a plurality 55 of nicks are shown near its end to further weaken the spindle where the curl occurs.

Fig. 4^b shows a still further modification, the lower end of the spindle being ringed to thus weaken the material where the curl 60 will occur.

Fig. 5 is a perspective of the tag or seal before the same is attached, and an awl for applying the same, and

Fig. 6 is a view showing the spindle before the application of the cap to the head thereof.

Referring now more particularly to the several views, and specifically to Fig. 6, it will be seen that I construct the seal of a 70 rod or wire 1 of aluminum of very limited ductility and then bend the upper end (lower end in Fig. 6) to form the arm 2, and the loop 3. The arm 2 is bent sharply at right angles to the spindle as at 4, and I make this bend preferably with a pair of pliers or any other square edged tool, so that the bend will be a sharp one.

The loop 3 has a certain resiliency so that it may be fitted within a cap 5 having the flange 6, which is pressed tightly inwardly so that after the loop 3 is sprung within the same, the cap will remain upon the loop, thus forming the completed head of the tag or seal. The upper surface of this cap may be provided with a monogram or trademark or brand, and as this cap is formed of aluminum, it will take a clear cut impression 85 from any suitable dies.

To apply this tag or seal to a ham, an awl 8 is provided which is passed through the upper end of the ham as at 9, the spindle 1 extending within the awl and after the awl has been passed within the ham, it will be pulled therethrough leaving a short shank 95 or portion of the spindle extending beyond the side of the ham.

A wrench having a head 10 is provided, this wrench having the nose 11 and lip 12 so that a few turns of the wrench will curl the end of the spindle as at 13, thereby tightly pulling the cap 5 of the tag against the ham and securely sealing the article.

Although the metal spindle is bent sharply at 4, the ductility of the metal is such that the seal or tag may be normally

applied without the head or cap being broken from the spindle, but, on the other hand, should anyone pull or pry at the cap and try to twist the same or pull it from the tagged article, the cap will break from the spindle at the bend 4 and thus destroy the seal.

The ductility of the metal also is such that should the coil 13 subsequently be bent, 10 or unwarrantably tampered with, this also will snap and thereby shorten the spindle 1. The original length of the spindle 1, of course, will be relatively short, in other words, just long enough to pass through the narrowest dimension of a ham.

From the foregoing it will be seen that I have produced a seal which is exceedingly cheap to manufacture and wherein the head may be impressed with a monogram or 20 trademark to denote the goods, and wherein the slightest pulling on the cap 5 will snap the loop and cap from the spindle. On the other hand, the construction of the seal is such that it will not snap when the curl 13 is originally formed on the outer end of 25 the spindle, in pulling the tag tightly against the ham, as the strain will be directly along the shank, whereas any prying of the cap will cause the strain to be 30 at right angles to the shank or spindle and, of course, snap off the head.

I am aware that it is old to form a spindle with a loop at its upper end and the arm from the loop extending at right 35 angles to the shank and the placing of a cap about the loop, such as a hatpin, but in that instance, any snapping of the spindle or shank at the bend was to be avoided and metal of high ductility was used, while 40 in the present instance, a metal of low ductility is used purposely, so that any prying of the cap will snap the spindle.

It will thus be seen that in this form of tag I may use a spindle of very low ductility and put a round curl on the end so 45 that any unwarranted straightening of the curl will snap the same, or will even snap the head from the spindle. Again, inasmuch as it is often hard to procure aluminum rods or wire of very limited ductility, I can purchase aluminum wire of normal 50 ductility and ring or nick the lower end and then curl the same, and the thus weakened spindle will snap at its lower end if the curl is maliciously tampered with.

It will also be seen that the manufacturing of the seal is relatively inexpensive and numerous dies may be made for properly marking the head as desired.

Many slight changes might be made 60 without in any way departing from the spirit and scope of the invention.

Having thus described my invention what I claim as new and desire to secure by Letters Patent is:—

1. A seal or tag comprising a spindle formed of metal of limited ductility, and the shank of the spindle being normally straight throughout its length and adapted to fit within an awl, the upper end of the 70 spindle being bent at right angles to the spindle and then formed in a loop, a cap supported by said loop and the bend of the spindle being the weakest point of the tag, and the lower end of the spindle adapted to be curled after the tag is applied. 75

2. A seal or tag comprising a spindle substantially straight throughout its length and adapted to be inserted in an awl and the spindle then bent at right angles at one end and then formed into a loop also positioned at right angles to the spindle, a metal cap on said loop, the lower end of the spindle being curled after the tag is applied, and the ductility of the metal being 80 such that any prying of the cap will snap the same from the spindle and any subsequent bending of the curl will also snap the curl from the spindle. 85

3. A seal or tag comprising a spindle, 90 normally straight throughout the greater portion of its length and adapted to be placed in an awl to pierce the article to be tagged and one end of said spindle having a short arm bent sharply at right angles to the spindle to thereby fatigue the metal at the bend; a loop formed at the end of said arm to support a fanciful cap, a fanciful cap, the lower end of the spindle adapted to be curled after the same has been placed through the tagged article, the ductility of the metal being such that the cap and loop will snap from the spindle if the same are tampered with. 95

4. A seal or tag for meat comprising a 100 spindle formed of aluminum of relatively low ductility and normally straight throughout its greater portion and adapted to be placed in an awl to pierce the article to be tagged, and having a loop formed at its one end at right angles to the spindle and the metal fatigued at the point of the bend on the said loop, a metal cap adapted to receive the loop of said spindle, the lower end of the spindle adapted to be curled to pull the loop and cap tightly against the article tagged and the loop arranged to break front the spindle if the cap is pried upwardly, and the ductility of the spindle being such 110 that the curl will break from the spindle if the same is subsequently bent. 115

5. A seal or tag comprising a spindle 120 formed of metal, the upper end of the spindle being bent to form a loop, the shank of the spindle being substantially straight and adapted to fit within an awl to pierce the article to be tagged, a cap engaging said loop, the lower end of the spindle being nicked to thereby weaken the same, and this end being of sufficient 125

strength to stand an initial bending, but incapable of withstanding a subsequent bending.

6. A seal or tag comprising a spindle formed of aluminum, said spindle being normally straight throughout the greater part of its length and adapted to fit within an awl to pierce the article to be tagged, and a portion of the spindle formed in the

shape of a loop, a cap supported by said loop and the lower end of the spindle being ringed to thereby greatly weaken the same to permit the spindle to be initially curled, but incapable of withstanding a subsequent uncurling.

In testimony whereof I affix my signature.

FORREST G. PURINTON.
